UNITED STATES PATENT OFFICE.

NORMAN V. HOLMES AND SHERMAN H. ARP, OF CHICAGO, ILLINOIS, ASSIGNEES TO SEARS, ROEBUCK AND COMPANY, OF CHICAGO, ILLINOIS, A CORPORATION OF NEW YORK.

SPRINKLER-HEAD CLOSER.

1,189,820.

Specification of Letters Patent.

Patented July 4, 1916.

Application filed December 20, 1915. Serial No. 67,744.

to all whom it may concern:

Be it known that we, NORMAN V. HOLMES and SHERMAN H. ARP, citizens of the United States, residing at Chicago, in the county of Cook and State of Illinois, have invented certain new and useful Improvements in Sprinkler-Head Closers, of which the following is a specification.

Modern buildings are equipped with fire extinguisher systems, comprising pipes adapted to conduct water to outlets in the form of sprinkler heads located at suitable places throughout the building for automatically discharging water in case of fire. These sprinkler heads are normally closed by heat susceptible closures, the latter being adapted to be affected by the heat from a fire to permit the closure to open and allow water to escape from the sprinkler head. When the fire is extinguished or is under control, the sprinkler heads are temporarily closed by mechanical devices until the water supply can be shut off at the base, and in case of small fires it is desirable that the closing of the sprinkler heads be effected promptly, otherwise the damage from the escaping water might greatly exceed that of the fire.

One of the objects of this invention is to produce an improved sprinkler head closing device which is adapted to be easily associated with a sprinkler head and is quickly and conveniently operable to close the outlet thereof.

Further objects are to produce a device which is adapted to engage the sprinkler head in a novel manner; in which springs and independent locking devices are dispensed with; and which comprises toggle joint means for operating the two main jaws or sprinkler-head-engaging parts of the device.

Further objects and advantages relating to details of construction will be apparent from the following description.

In the accompanying drawings, Figure 1 is an elevational view illustrating a sprinkler head and a closing device mounted thereon which embodies the features of our invention. The handles or operating levers of the device are shown as partially broken off in Figs. 1 to 4. Fig. 2 is a perspective view of the closer in an open position. Fig. 3 is a section in the plane of line 3—3 of

Fig. 1. Fig. 4 is a plan view of the closer. Figs. 5 and 6 are sections on lines 5—5 and 6—6, respectively, of Fig. 1.

In the drawings, 1 indicates the supply pipe of a sprinkler system and 2 the sprinkler head, said head comprising the usual enlargement 3 and the yoke portion 4 opposing the outlet of the head and carrying the spreader 4a.

Our improved closing device comprises a bar 5, one end of which is shaped to pass between the sides of the yoke 4 and carries a yieldable stopper 6 of suitable material, such as rubber, adapted to close the outlet of the sprinkler head. The opposite end of the bar 5 in the present instance provides one of the operating handles of the device. An arm 7 is pivoted at one end at 8 to the bar 5 about midway between the ends of the latter and the opposite end of said arm is forked to embrace the supply pipe or the shank of the sprinkler head, said forked end being shaped to take a bearing against the enlargement 3 on said head, as shown in Fig. 5. When viewed in plan (Fig. 4), the stopper 6 registers with the fork of the arm 7.

The arm 7 and the bar 5 are arranged to be drawn toward each other to force the stopper 6 tightly against the outlet of the sprinkler head, by means of a lever 9 pivoted at 10 to the bar 5 at the opposite side from the arm 7, said lever providing the other operating handle of the device. The lever 9 is connected to the arm 7 by means of a pair of links 11 which pass at opposite sides of the bar 5. In the present instance, the lever 9 is of bell-crank formation and the centers 12 and 13 of the links are so located with relation to the center 10 of the lever 9 that when the lever and the bar are pressed toward each other to the position shown in Fig. 1, the links will throw over the pivotal center of the lever 9 and the tension on said links will act to hold the lever 9 and the bar 5 close together, in which position the stopper 6 will be tightly clamped in its closing position.

In use, the device is opened to the position shown in Fig. 2 and is associated with the sprinkler head by inserting the end of the bar 5 through the yoke 4 and causing the forked end of the arm 7 to embrace the shank of the head. The handles of the de-

vice, to-wit, the opposite end of the bar 5 and the lever 9, are then swung toward each other, which acts to draw the bar 5 and the arm 7 together and force the stopper 6 tightly against the end of the outlet of the sprinkler head, thus cutting off the flow of water from said head. When the links 11 have thrown over the center, as shown in Fig. 1, the device will remain in firmly 10 locked position on the sprinkler head and needs no positive locking means to hold it in its operative position. In removing the device the bar 5 and lever 9 are merely swung away from each other to separate the 15 bar and the arm 7 as shown in Fig. 2, when the device may be withdrawn from the sprinkler head.

While the device shown in the drawings represent the preferred embodiment of our 20 invention, it should be understood the invention is not limited to the particular arrangement of parts disclosed, but is capable of various modifications within the scope of the appended claims.

25 We claim as our invention:

1. A sprinkler head closer comprising a bar adapted to be passed through the yoke of the sprinkler head and carrying a stopper, an arm pivoted at one end to said bar 30 and forked at its other end to embrace the shank of the sprinkler head and engage the enlargement thereon, a lever pivoted to said bar at the opposite side thereof from said arm and at a point between the ends of said 35 arm, and a pair of links each pivoted at one end to said lever adjacent to its pivotal axis, each link being pivoted at its other end to said arm between the ends of the latter and the links lying at opposite sides of said bar, 40 the respective centers of the links and said lever being arranged so that the links will throw over center and lock the bar and arm in their drawn together position when the lever and bar are swung together.
- 45 2. A sprinkler head closer comprising a

stopper-carrying member, an opposed member pivoted thereto and adapted to engage a part on the sprinkler head, a lever pivoted to the stopper-carrying member, and a link connecting said lever to said opposed member. 50

3. A sprinkler-head closer having, in combination, a bar carrying a stopper and constituting a handle, a bell-crank lever pivoted to one side of the bar relatively close to the stopper, one arm of said bell-crank lever constituting a handle, said handles being adapted to extend in approximately parallel relation, a bifurcated arm pivoted to the opposite side of the bar, and a link connecting the other arm of said bell-crank lever to said bifurcated arm, said link being arranged to swing over center to lock the stopper and the bifurcated arm against separating movement. 60

4. A sprinkler head closer comprising a bar constituting a handle, a forked arm pivoted thereto, a stopper carried by said bar, a lever pivoted to said bar relatively close to the stopper and constituting a handle, and a link connecting said lever to said arm for operating the arm and the bar with relation to each other. 70

5. A sprinkler head closer comprising a bar constituting a handle and carrying a stopper, an opposed member pivoted to one side of said bar, a bell-crank lever pivoted to the opposite side of said bar relatively close to the stopper, one arm of said bell-crank lever constituting a handle, and links located at opposite sides of said bar and connecting the other arm of said bell-crank lever to said member. 75 80

In testimony whereof we hereunto set our hands.

NORMAN V. HOLMES.
SHERMAN H. ARP.

In the presence of—

JOHN HIGGINS,
F. E. ROBERTS.
